UNITED STATES PATENT OFFICE.

CLYDE M. NYE, OF EMMETT, IDAHO, ASSIGNOR TO JOHN H. NYE, OF EMMETT, IDAHO.

SWITCH.

1,310,430.

Specification of Letters Patent. Patented July 22, 1919.

Application filed June 20, 1918. Serial No. 241,029.

To all whom it may concern:

Be it known that I, CLYDE M. NYE, a citizen of the United States, residing at Emmett, in the county of Gem and State of Idaho, have invented a new and useful Switch, of which the following is a specification.

The subject of this invention is a switch such as is used for making and breaking an electric circuit.

The main object of the invention is the provision of means for displaying a signal on an automobile when the same is to be reversed or backed.

Another object of the invention is the provision of means operated by the reversing lever for displaying a signal.

The invention also contemplates generally improving the construction and enhancing the utility of electric switches.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawing, wherein:

Figure 1 is a view in side elevation of a switch constructed in accordance with the invention, shown applied, the position assumed by the reversing lever when in reverse being shown in dotted lines;

Fig. 2 is an enlarged view in side elevation of the switch;

Fig. 3 is a plan view of the same;

Fig. 4 is a rear end elevation;

Fig. 5 is a fragmentary front end elevation showing the mounting of the switch elements;

Fig. 6 is a diagrammatic view of the switch and its circuit.

Referring to the drawing by numerals of reference:

The usual plate is shown at 1, which is fastened to the floor of an automobile, as indicated, and which is suitably slotted to allow proper play of the control lever 2. Secured to the floor of the automobile, immediately in front of the plate 1, is the

switch which forms the subject of this invention.

The switch consists of a base plate 3, the forward end of which is upturned, as at 4. Upon this plate 3 is secured, by screws or otherwise, an arch 5 which is positioned adjacent the rear end of the plate, and which extends transversely of the plate. Secured upon the top of the arch 5 is a horizontally disposed bar 6 which extends longitudinally of the switch structure, and which has its forward end 7 downwardly bent, and this end is positioned to the rear of and in spaced relation to the upturned end 4 of the plate 3. The ends 4 and 7 are apertured to receive the threaded end of a horizontally disposed rod 8 which is held in place in said apertures by the clamping nuts 8' and which also extends longitudinally of the switch. The lower end of the bent end 7 is apertured to receive the hook end of a retractile spring 9.

The rear end of the bar 6 is forked and the fork portions apertured to receive a pin 10 which serves to fulcrum a lever 11 on the bar. The downwardly extending arm of the lever 11 has the rear end of the retractile spring 9 fastened thereto. This spring serves to draw the lower end of the lever 11 forwardly and the movement of the lower end or arm of the lever in such direction is limited by the rear end of the rod 8, against which the lever strikes.

Secured to the upper arm of the lever 11 by a bolt 12 and nuts 12' which are threaded thereon, is a wedge block 13, while on the rearwardly projecting end of the bolt 12 is secured a fork 14, which is adapted to straddle the lever 2 when the lever is thrown to reverse position, and engage the lever so that the lever 2 may rock the lever 11 against the tension of the spring 9, and so throw the wedge block 13 forwardly to separate the resilient leaves of the switch, as will be set forth.

A support 15 is secured to and rises from the bar 6, near the forward end of the bar, and to this support are attached, by the screws 16 or otherwise, the insulated terminals 17, on the forward ends of which are the upstanding connector ends 18. The terminals 17 are of leaf formation and between these terminals and insulated from them and from the support 15 are the resilient leaf switch members 20 which are in

electrical connection through a bridging strip 20'. Circuit wires 19 are connected to the connector ends 18 for the purpose of conducting current from a suitable source 5 of electrical supply to the switch.

The circuit wire 19 which leads from one terminal 17 is connected to one pole of a suitable source of electrical supply, such as the battery 21, the other pole of which is 10 grounded as at 22. The wire 19 connected to the other terminal 17 is grounded, as at 24, and in this portion of the circuit are interposed a lamp 23, which is situated at the rear end of the automobile, and the usual 15 light circuit switch 25.

As will be understood, when the switch 25 is closed, the device is in condition for operation. When the lever 2 is thrown to reverse it comes into contact with the fork 14 and 20 rocks the lever 11, thereby throwing the 25 wedge block 13 between the forward ends of the resilient leaf members 20, and causing them to contact the terminals 17. This will place the terminals 17 in electrical contact 30 through the members 20 and the bridging strip 20', and thus complete the circuit from the battery 21 through the lamp 23. This causes the lamp to light and so notifies one to the rear of the automobile that the same

Having thus described the invention, what is claimed as new and sought by Letters Patent, is:—

1. A switch, including a base plate, an 35 arch secured to and rising from the base

plate, a horizontally disposed bar secured to the arch, a lever fulcrumed at one end of the bar, a wedge block carried by the lever, resilient means for holding the lever in normal position, a support on the bar, terminals secured to and insulated from the support, and resilient members separated to contact and bridge the terminals when the wedge block is swung between the members by the rocking of the lever, and means for rocking the 40 lever.

2. A switch including a base plate having an upturned end, an arch secured to the base plate, a bar attached to the arch and having a downturned end in spaced relation to the 50 upturned end of the base plate, a rod adjustably secured to the said ends and forming a stop, a lever fulcrumed on one end of the bar, resilient means for normally holding the lever against the rod, a wedge block 55 carried by the lever, terminals mounted on the bar and insulated therefrom and from each other, a resilient bridging member adapted for separation by the wedge block to contact the terminals, and means for rocking the lever to swing the wedge block between the bridging member.

In testimony that I claim the foregoing as my own, I have hereto affixed my signature in the presence of two witnesses.

CLYDE M. NYE.
